(57) **CLAIM**

I claim the ornamental design for a transparent package for confectionary, as shown and described.

DESCRIPTION

FIG. 1 is a perspective view of a transparent package for confectionary showing the new design;

FIG. 2 is a top plan view thereof;

FIG. 3 is a side elevation view thereof; and,

FIG. 4 is a bottom plan view thereof.

It is noted that all of the side views of the claimed transparent package for confectionary are identical.
